STARCH MILL REEL

Karl R. Clendening, Cedar Rapids, Iowa

Application February 16, 1935, Serial No. 6,826

3 Claims. (Cl. 209—407)

My present invention relates to starch mill reels and particularly to a construction making it possible to easily and quickly make repairs when one or more of the reel silks becomes broken. 5 Among the objects of this invention are to provide a reel of the character indicated which is so constructed that the work of replacement of broken or torn silks is reduced to a minimum; to provide a structure of the character indicated in 10 which most of the work of replacing torn silks can be done away from the reel, where conditions for doing the work are better than in the reel bed; to provide a structure of the character indicated in which individual silks may be removed 15 and new ones substituted with a minimum of work and loss of time in shut-downs; to provide a structure for the purpose indicated in which the number of screws which must be removed for the replacing of a torn or broken silk is reduced 20 to a minimum; and such further objects, advantages, and capabilities as will hereafter appear and as are inherent in the construction disclosed herein. My invention further resides in the combination, construction, and arrangement 25 of parts illustrated in the accompanying drawing and, while I have shown therein what is now considered the preferred embodiment of this invention, I desire the same to be understood as illustrative only and not to be interpreted in a 30 limiting sense.

In the drawing annexed hereto and forming a part hereof,

Fig. 1 is an end view of a reel embodying my present invention;

Fig. 2 is a side view of a portion of such a reel, part thereof being broken away;

Fig. 3 is a fragmentary section taken approximately along a plane indicated by the line 3—3, Fig. 2;

Fig. 4 is a face view of one of the panels comprising a frame and a silk;

Fig. 5 illustrates a section through the structure shown in Fig. 4.

Reference will now be made in greater detail to the annexed drawing for a more complete disclosure of this invention. From the drawing it will be seen that the reel comprises an axial supporting member 1, spokes 2, ribs 3, end members 4, and panels 5. Preferably, the spokes 2 extend 45 through the supporting member 1 and the ribs 3 so that it is possible to remove same by driving them endwise through the supporting member 1 and ribs 3. The spokes are not arranged in the same plane but are staggered with respect to 50 each other, as indicated in Fig. 2.

As shown in Fig. 1, the ribs 3 are grooved for the reception of the panels 5 which are held in place along one edge by the strips 6 which have screws 7 extending therethrough and into the ribs. The screws 7 do not extend through the frame 8 of the panels but simply clamp the strips 6 against same so as to hold one edge of the panels tightly against the ribs. The opposite edge of each panel is held in place by a screw 9 passing therethrough and into the rib. To remove a panel 5, its screw 9 is removed and about three of the screws 7 are loosened to permit the strip 6 to be sprung out sufficiently so that the panel may be drawn out. Another panel is then substituted for this, this new panel having been 15 previously equipped with a new silk so that it is all ready to be inserted in the place of any panel removed from the reel.

As shown in Figs. 3 and 5, the end members of the frames 8 are rabbeted, as indicated at 10, so 20 as to produce a tight joint between the panels, thus preventing the starch from leaking through between them. The rabbeted ends overlap and have space between them to permit expansion of the frames without bulging, it being understood that these reels have a mass of water and milled substance passing through them continuously. Due to this fact, the tendency is for the wood to expand upon absorption of moisture and, unless provision is made for this expansion, 25 distortion is likely to result.

From the foregoing it will be apparent that, when a silk is broken or torn, it will not be necessary to remove a frame extending from end to end of the reel and containing, customarily, six 35 silks but that, instead, a single panel may be removed and replaced by one which has been previously prepared at some convenient location away from the reel. When a frame which extends the full length of the reel has to be removed, it is necessary to remove from sixteen to forty-eight screws, each from two to two and one-half inches long. The tendency is for the repair man to drive these screws into place with a hammer, when restoring the frame to its position on the reel. This results in rapid deterioration and breakage of the reel ribs, necessitating many replacements. Also, when a silk is torn from its frame, it is not unusual for one or more tacks to be dropped into the reel bed where it is 40 lost in the water-starch suspension. When the repair work is done away from the reel and all that it is necessary to do is to substitute a fresh panel for the one having the broken silk, the time of shut-down is reduced to a minimum, 45 50 55

perhaps two or three minutes in comparison with twenty to thirty minutes necessary when a frame extending the full length of the reel must be removed. There are many other advantages resulting from this new construction which has been needed for many years but it is believed that the advantages thereof will be obvious to one skilled in the art upon consideration of the foregoing disclosure.

10 It is of course understood that the specific description of structure set forth above may be departed from without departing from the spirit of my invention as set forth in this specification and the appended claims.

15 Having now described my invention, I claim:

1. A starch mill reel having a plurality of flat faces each consisting of a plurality of panels, each panel comprising a frame supporting a silk, the frames having their opposite ends rabbeted upon opposite sides, the ends of the frames, where rabbeted, overlapping but being longitudinally spaced to permit expansion of the frames.

2. A starch mill reel comprising a skeleton and panels supported thereby, said skeleton comprising end supports, spokes, and longitudinally extending ribs, said panels comprising open frames having silks secured tightly thereto, the

reel being divided into a plurality of longitudinally aligned sections, and each section having one panel upon each of its lateral faces, the ends of the panel frames being rabbeted upon opposite sides and the frames being arranged with an end of each overlapping the proximate end of one of the adjacent panels.

3. A starch mill reel comprising a skeleton and panels supported thereby, said skeleton comprising end supports, spokes, and longitudinally extending ribs, said panels comprising open frames having silks secured tightly thereto, the reel being composed of a plurality of longitudinally aligned sections, each section having one panel upon each of its lateral faces, the ends of the panel frames being rabbeted upon opposite sides and the frames being arranged with an end of each overlapping the proximate end of one of the adjacent panels, and strips secured to the ribs, each strip overlapping one edge of all of the panels on one face of the reel, the opposite edges of the panels being secured in place by an individual fastening means for each panel which enables the removal of a single panel without disturbing any other panel.
